FIG. 7.

INVENTOR.

HENRY K. HALL

By Wilson & MacCann
ATTYS.

UNITED STATES PATENT OFFICE.

HENRY K. HALL, OF ROCKFORD, ILLINOIS.

SHADE FIXTURE.

Application filed March 21, 1923. Serial No. 626,465.

To all whom it may concern:

Be it known that I, HENRY K. HALL, a citizen of the United States, residing at Rockford, in the county of Winnebago and

5 State of Illinois, have invented certain new and useful Improvements in Shade Fixtures, of which the following is a specification.

This invention relating in general to curtains, shades and screens, has more particu-

10 lar reference to shade fixtures, such as are supported for vertical adjustment. This adjustment is for the purpose of positioning the shade to cover any desired portion of the window, leaving a greater or less amount 15 of the window exposed either at the top or bottom so that the desired lighting effects and ventilation may be obtained according to weather conditions and the room requirements.

20 The primary object of the present invention is to provide an improved shade fixture of this kind, with the view to simplifying the construction so that it may be economically produced and will be thoroughly practical for the purposes in mind, and with the further view of ease and convenience of installation and adjustment.

In furtherance of the foregoing, my invention contemplates the provision of novel 30 means for supporting a shade characterized by suspension of the shade at its center by means of a flexible element, such as a cord trained over a pulley, and novel means for balancing, adjusting and guiding the shade, so that it will be properly positioned at all 35 times with relation to the window and may be easily raised and lowered.

Another object is to guide the suspended shade at its center on a taut wire or the 40 equivalent, which in connection with guide means which will be more fully described hereinafter, holds the shade at the proper level and prevents it from swinging from side to side.

45 In further regard to the suspension, I have aimed to provide a means for obtaining an approximate balance of the shade comprising a weight positioned on the hanger at the end opposite from the roller 50 spring, this weight being preferably permanently embedded in the hanger bar, and to further provide an adjusting means by which the shade may be balanced to a fine degree of nicety and retained in such balanced condition at any position to which it 55 may be set.

Other objects and attendant advantages will be appreciated by those skilled in this art as the invention becomes better understood by reference to the following description when considered in connection with the accompanying drawing, in which—

Figure 1 is a front elevation of a window frame, window and shade fixture operatively associated therewith embodying my invention;

Fig. 2 is a vertical section taken substantially on the line 2—2 of Fig. 1;

Fig. 3 is an enlarged front view of the shade hanger with the shade roller removed;

Figs. 4 and 5 are sections taken on the lines 4—4 and 5—5, respectively, of Fig. 3;

Fig. 6 is a fragmentary rear view of the hanger; and

Fig. 7 is a detail section taken on the line 75 7—7 of Fig. 6.

The shade roller 11 on which the shade 12 is wound, may be of any suitable or preferred construction. My invention, however, in certain respects is intended for application to shade rollers of the well known type having a spring in one end for winding the shade. My invention contemplates as mentioned above, the provision of means for suspending and guiding this unequally balanced shade roller in a simple and practical manner and so that it may be easily and conveniently adjusted for service requirements.

The shade roller will be supported on a 90 suitable hanger 13 through the agency of the usual brackets 14. This hanger for purpose of economy in the cost of manufacture is preferably in the form of a wooden bar bored or otherwise shaped at one end 95 for the reception of a metal weight 15. The purpose of this weight is to counterbalance the weight of the spring and appurtenant parts at the opposite end of the roller, this balance being effected with relation to the 100 central suspension of the hanger by means of a cord or other flexible element 16. It will be manifest that by lengthwise adjustment of the weight in the hanger bar, an approximate balance of the shade roller 105 and hanger will be obtained. A plug 17 covers the end of the weight hole in the hanger bar. In the present instance, the cord 16 is attached to the hanger bar through means of a metal bracket 18. Any 110 suitable means of attachment may, however, be employed. The hanger suspending cord

is trained over a stop pulley 19 of conventional construction, fixed to the top portion of the window frame 21. By manipulation of the cord 16 the shade hanger may be 5 raised and lowered as will be obvious, and supported at any elevation by locking the cord in the strop pulley.

In the preferred form of my invention, the ends of the hanger bar overreach the 10 sides of the window frame, and each end is equipped on its inner face with a suitable bumper or anti-friction device which will prevent such ends in their movement along the window frame from marring the 15 finish thereof, and will provide sliding contact with such frame, such as will not interfere with the balance and proper operation of the hanger. The bumper shown at present for illustrative purpose merely, is in 20 the form of a felt pad 22 secured by a screw 23 at each end of the hanger bar at the rear side thereof. Any form of bumper or the equivalent may, however, be employed.

For the purpose of guiding the shade 25 hanger for holding it against swaying in any direction and for maintaining a precise balance, so that it may be easily raised and lowered and will be held in the proper operative position, I have provided a central 30 guide and adjusting means which will now be described. The guideway is preferably in the form of a wire 24 stretched taut between the top of the window frame and sill 25 at a central position thereon. The 35 guide consists of a holder designated generally by 26, adjustably attached to the hanger bar as will be presently described, and carrying a guide element 27 which has an elongated hole through which the wire 40 24 passes. I prefer that the guide element shall be of wood, rubber or some material having a coefficient of friction so different from the wire as to prevent squeaking by sliding of the guide on the wire. The present 45 guide has reduced ends 28 which fit in holes in the spaced arms 29 of the holder and are firmly held in position thereon. The guide holder is attached to the rear side of the hanger bar centrally between its ends 50 by means of screws 31 and 32, the former of which provides a fixed fulcrum and the latter passes through an arcuate slot 33 in the upper end of the holder. It will be manifest viewing Fig. 6, that when these 55 screws are loosened the hanger may be tilted about the screw 31 as a fulcrum for the purpose of securing a fine adjustment or balance of the hanger and shade with respect to the guide wire, and that when 60 this adjustment is obtained it may be made permanent by tightening both screws. Thus while an approximate balance is obtained by the balance weight in the end of the hanger bar, the precise and final balance is 65 obtained by relative adjustment of the

hanger bar and guide. When now the hanger is raised and lowered by means of the cord 16 it will be perfectly balanced and will slide freely and easily.

The guide wire 24 may be tightened by 70 any suitable means, and I prefer to attach it at its upper end to a screw eye 34 fastened to the window frame and at its lower end to a threaded element 35 which is threadedly engaged in a plate 36 fastened to the window sill and has a flattened thumb-piece head 37 provided with a hole 38 for attachment to the wire. It will be manifest that by turning the thumb piece 37, the member 35 may be screwed into the plate 75 80 for tightening the wire to the necessary degree, and that by this simple means or the equivalent, the wire may be easily kept taut.

My improved shade fixture may be made 85 in various sizes and applied to windows of any kind. It should be understood, therefore, that the example disclosed herein is for illustrative purpose merely and that changes might be made in the size, shape and 90 arrangement of parts and of materials used without departing from the spirit and scope of the invention as expressed in the appended claims.

I claim:

1. A shade fixture comprising a shade roller hanger, means for suspending the hanger at a central position thereon, a vertical guide element at said central position, a guide slidable on said element, a holder for attaching said guide to the hanger, and means connecting the holder to the hanger comprising a fulcrum screw and a screw passing through an arcuate slot in the hanger, whereby the hanger may be tilted on said 100 fulcrum screw for balancing adjustment on said guide without sidewise displacement and whereby the hanger may be secured in the adjusted position by said second mentioned screw.

2. The combination of a window frame, of a shade fixture comprising a spring shade roller, a hanger therefor overreaching the sides of the window frame, a bumper on each end portion of the hanger at the side adjacent to the window frame, a cord attached to the hanger at a central position thereon, a stop pulley on the top portion of the window frame over which said cord is trained for suspending the hanger and adjusting it 115 vertically, a weight on the end portion of the hanger opposite from the roller spring for securing an approximate balance of the hanger, a wire guide attached to the top and bottom portions of the window frame 120 medially between its sides and adapted to be drawn taut, and a guide slidable on said wire and pivotally attached to the hanger on a horizontal axis so that said hanger is 125 adjustable about said pivot for accurate bal- 130

ance, and means for fixedly securing the hanger in any adjusted relation to the guide means.

3. A shade fixture of the character described comprising, in combination, a spring-operated shade roller, a hanger bar, a bracket on each end of the hanger bar between and upon which the roller is mounted, a hanger-suspending cord attached to 10 said bar centrally between the ends thereof, a vertical guide wire disposed centrally between the ends of said hanger bar adjacent thereto, guide means on the hanger bar slideable on said guide wire, and a pivotal connection on a horizontal axis between the 15 hanger bar and guide means, whereby the hanger bar may be tilted on said guide means for securing balancing adjustment without sidewise displacement of the hanger 20 bar.

4. A shade fixture of the character described comprising, in combination, a spring-operated shade roller, a hanger bar, means supporting the roller on the hanger 25 bar, a hanger-suspending cord attached to said bar centrally between the ends thereof, a vertical guide wire disposed centrally between the ends of said hanger bar adjacent thereto, guide means on the hanger bar slideable on said guide wire, a weight on the 30 end of the hanger bar opposite from the spring-carrying end of the roller adjustable lengthwise on said bar for securing approximate balance of the suspended part, a 35 pivotal connection on a horizontal axis between the hanger bar and guide means, whereby the hanger bar may be tilted on said guide means to secure accurate balance

of the suspended part, and means for securing the hanger bar to the guide means in any tilted position.

5. A shade fixture of the character described comprising, in combination, a spring-operated shade roller, a hanger bar of wood, a bracket on each end of the hanger bar between and upon which the roller is mounted, a hanger-suspending cord attached to said bar centrally between the ends thereof, a vertical guide wire disposed centrally between the ends of said hanger bar 45 adjacent thereto, guide means slideable on said guide wire, and pivotally attached to the hanger bar for adjustment and adapted to be fixedly connected thereto after adjustment, the hanger bar being bored longitudinally inwardly from its end opposite from the spring-carrying end of the shade roller, and a weight inserted into the bored hole 50 for securing approximate balance of the hanger and roller on the guide wire.

6. A shade fixture comprising, in combination, a hanger bar, a shade roller supported on the front of said bar, a cord for suspending the hanger bar from a central point thereon, a vertical guide wire at the 65 back of the hanger bar, and means for guiding the hanger bar upon said wire comprising vertically spaced arms extending rearwardly from the hanger bar and a wire-engaging guide means attached to each of 70 said arms and being of a non-metallic material, and means for effecting balancing adjustment between the guide means and hanger bar.

HENRY K. HALL.
